UNITED STATES PATENT OFFICE.

CHARLES HOFER, OF NEWARK, NEW JERSEY.

ARTIFICIAL LIMB.

1,305,721.

Specification of Letters Patent. Patented June 3, 1919.

Application filed May 27, 1918. Serial No. 236,746.

To all whom it may concern:

Be it known that I, CHARLES HOFER, a citizen of the United States, residing at Newark, in the county of Essex and State 5 of New Jersey, have invented certain new and useful Improvements in Artificial Limbs; and I do hereby declare the following to be a full, clear, and exact description of the invention, such as will enable others 10 skilled in the art to which it appertains to make and use the same, reference being had to the accompanying drawings, and to characters of reference marked thereon, which form a part of this specification.

15 This invention has reference, generally, to improvements in artificial limbs; and, the present invention relates, more particularly, to a novel construction of artificial limb, in the form of an arm, with a view of providing a simply constructed and efficient arrangement of mechanism for operating and flexing the artificial fingers, and thumb of the device, so as to enable the person to securely grip and carry articles of considerable weight, and to otherwise use the artificial limb.

20 The invention has for its principal object to provide in connection with the mechanism for manipulating the fingers and thumb of the artificial limb in connection with each finger and the thumb, suitably disposed coiled springs, having ready flexibility, each spring being secured at one end to a metal shield, shell or casing, each spring being 25 tipped at its opposite end with a cap or cup-shaped member, and each spring being partially covered or inclosed by a flexible covering-member, so as to permit of the proper drawing of the usual glove over the said fingers 30 and thumb.

25 The invention has for its further object to provide in connection with the said shield, shell or casing, a slotted boot or legging-like member provided with an arrangement of eyelets and a lacing for securing the artificial limb to the stump or mutilated portion of the arm, the said boot or legging-like member being also provided with a box 40 forming a guide in which is movably disposed a slide and flexible connections for connecting said slide with the previously mentioned springs, and pivotally connected with said box and the said slide is a slotted cam-lever for actuating the said slide when 45 the fingers and thumb are to be flexed.

50 Other objects of the present invention not

at this time more particularly enumerated will be clearly understood from the following detailed description of the present invention.

60

With the various objects of the present invention in view, the said invention consists primarily, in the novel artificial limb hereinafter set forth; and the present invention consists, furthermore, in the novel arrangements and combinations of the several devices and parts, as well as in the details of the construction of the said parts, all of which will be more fully described in the following specification, and then finally embodied in the clauses of the claims which are appended to and which form an essential part of the said specification.

70

The invention is clearly illustrated in the accompanying drawings, in which:—

75

Figure 1 is a top view of the artificial limb; Fig. 2 is a side view of the same, and Fig. 3 is a bottom view of the said limb.

Fig. 4 is a view, similar to Fig. 2, showing the operating parts of the mechanism in their actuated and locked relation, with the fingers of the limb in their closed positions.

Fig. 5 is a horizontal sectional representation, taken on line 5—5 in said Fig. 2, looking in the direction of the arrow α , said view being made on an enlarged scale; Fig. 6 is a similar section, taken on line 6—6 in said Fig. 2, also looking in the direction of the arrow α , with certain elements of the device omitted from said view, said view 80 being also made on an enlarged scale.

Fig. 7 is a detail sectional representation taken on line 7—7 in said Fig. 2; and Fig. 8 is a transverse vertical section, taken on line 8—8 in said Fig. 6, looking in the direction of the arrow β , said view showing in connection therewith one manner of securing the flexing springs in position.

Similar characters of reference are employed in all of the said above described views, to indicate corresponding parts.

Referring now to the said drawings, the reference-character 1 indicates the complete artificial limb, representing one embodiment of the principles of the present invention, and the same comprises, in general, a main shield, shell or casing, as 2, of the general configuration shown in Figs. 1 to 4 inclusive, the same being formed at its longitudinally extending marginal portions with the flange-like elements or parts 3 and 4, having the slightly inwardly curved edge-portions 5,

105

110

substantially as shown in Figs. 3 and 8 of the drawings. The said shield, shell or casing 2 is also formed with the inclosing part 6 from which extends at one side thereof, a 5 suitably curved member or element as 7. Extending rearwardly from the said inclosing part 6 is a plate-like member or extension 8 of proper length, upon which is suitably mounted a correspondingly formed box, 10 as 9, which provides a suitable guide in which is movably disposed a slide of the general construction to be presently more fully described. In the closed top of said box is an elongated opening or slot 10, with 15 which is in communication at the one end thereof a short and angularly disposed open portion or recess, as 11, the marginal bounding edge-portion 12 providing a holding or retaining stop for the purposes hereinafter 20 more fully stated. At a point suitably near this stop is a projection 13 formed with a screw or pin-receiving opening or hole 14, in which is disposed a screw or pivot-post, as 15. Pivots mounted upon this screw or post 15 is the end-portion 17 of a cam-lever 16, said lever being provided with a cam-slot, as 18, and with a fingerpiece 19 at its opposite end for the manipulation of the 25 said lever. Suitably secured to the said 30 shield, shell, or casing 2, by means of rivets 20, or other suitable fastening means, and by means of rivets 21, or other suitable fastening means, along the marginal edge-portions of the said plate-like member or extension 8, 35 is a cuff, boot, or legging-like member, as 22, usually of leather, although other suitable material may be employed, the said member 22 being slitted or open, as at 23, and being provided with an arrangement of 40 eyelets or perforations 24, and a lacing 25, for suitably securing the same about the mutilated end or stump of the limb.

Referring now to Figs. 6 and 8 of the drawings, it will be seen, that there is secured to the inner face of the previously mentioned shell or casing 2, so as to be located between the flange-like elements or parts 3 and 4, by means of rivets 26, or in any other suitable manner, a plate 27 which 50 is provided with suitably disposed and longitudinally extending retaining or holding members 28, suitably pressed out of the metal body of the said plate, each member 28 being provided with a number of suitably and properly located holes or perforations 29. Suitably threaded in said holes or perforations, in the manner illustrated in said Fig. 8, are the inner end-portions of a series of coiled springs 30, four in number, as shown, 55 said springs under normal initial conditions extending forwardly, but being somewhat curved, as shown, and having mounted upon their free end-portions, suitably formed semi-ball-shaped caps, as 31, or the like. 60 65 The outer surface-portions of the coils of

said springs 30 are preferably partially covered with leather, as at 32, see Figs. 1, 2 and 4 of the drawings, one method of securing said leather members 32 upon the said springs 30 being by providing the said members 32 with holes or perforations 33 through which the coils of the springs are threaded, as shown. As will be understood, this arrangement of the four springs and their parts provide the artificial fingers of the device. Similarly and suitably secured to the inner surface of the previously mentioned curved member or element 7 is the inner end-portion of another spring, as 34, said spring under normal initial conditions extending 70 forwardly and being slightly curved, substantially as shown in the several figures of the drawings. Upon its free end-portion the said spring 34 has also mounted thereon a semi-ball-shaped cap 35, or the like. The 75 outer surface-portions of the coils of said spring 34 are also preferably partially covered with leather, as at 36, one method of securing said leather member 36 upon said spring 34 being by providing the said member 36 with holes or perforations 37 through which the coils of the said spring are 80 threaded.

The previously-mentioned slide is illustrated more particularly in Fig. 4 of the drawings, and the same consists, essentially, of an arrangement of pivotally connected or articulating links or short plates, as 38, 39 and 40, pins or pivots 41 and 42 being employed for the pivotal arrangement of the 90 said links. As shown, the link or plate 40 is provided with a series of holes or perforations 43, or other suitable means, for attachment to said link or plate of a number of flexible connections, in the form of tendons, as 44, which connections extend from the end of the box 9 and beneath and from the part 6 of the shield, shell, or casing 2. The several flexible connections 44 are passed, furthermore, into and through the 95 respective springs 30 and are finally securely attached at their free ends to the respective caps 31, substantially in the manner illustrated in Fig. 7 of the drawings. The link or plate 38 is provided with a suitably disposed post 45 which extends in an upward direction and is movable in the elongated opening or slot 10 of the closed top of the box 9, the said post being provided upon its 100 upper end, above the said top, with an enlargement or head, as 46, for holding the said parts in their assembled relation, but arranged so that there will be no binding 105 action to prevent movement of the slide.

Having in the foregoing described the 110 general construction and arrangement of the devices and parts comprising the artificial limb, I will now briefly set forth its operation for the purpose of grasping and carrying an article.

Suppose the artificial limb has been secured in its position upon the stump or mutilated end of an arm of the person, and that the several parts are in their normal initial positions indicated in Figs. 1, 2, 3 and 5 of the drawings, and it is desired to grasp an article, all that is necessary is to move the lever 16 from the position indicated in Fig. 3 to that shown in Fig. 4 of the drawings, moving the pin or post 46 into the opening 11 and against the stop-edge 13 whereby the several parts will be retained in their fixed or locked relation for carrying purposes, the pull upon the flexible connections or cables 15 44, and the fixed end-portions of the springs 30, causing the free end-portions of said springs and consequently the finger-members to assume the closed or carrying relation of the same, as will be clearly evident. 20 As soon as the lever 16 is moved in the direction of the arrow y , see Fig. 4, the post or pin 46 is withdrawn from its retaining engagement with the stop-edge 13, and, the springs 30 tending to straighten out, the various parts will again assume their normal 25 initial positions, indicated in said Figs. 1, 2 and 3 of the drawings.

Of course I am aware that some changes may be made in the arrangements and combinations of the various devices and parts, as well as in the details of the construction of the same, without departing from the scope of my present invention as set forth in the foregoing specification and as defined in the 30 claims appended hereto. Hence, I do not limit my invention to the exact arrangements and combinations of the various parts as described in the foregoing specification, nor do I confine myself to the exact details of 35 the construction of the said parts as illustrated in the accompanying drawings.

I claim:

1. An artificial limb comprising a main tubular wrist portion and a forwardly extending member connected with said wrist portion, a series of coiled springs, each spring being attached at one end-portion to said forwardly extending member, button-members mounted upon the free ends of said 40 springs, a cuff-attachment connected with and extending rearwardly from said tubular wrist portion, means connected with said cuff-attachment for securing said artificial limb to the mutilated portion of the limb of 45 a person, flexible connections extending into and through said springs, said flexible connections being secured at one end to said button-members, a plate also connected with and extending rearwardly from said tubular 50 wrist portion, a box mounted upon said plate, said box being provided with an elongated opening, and an angularly disposed open portion in communication therewith, a slide within said box, said slide comprising 55 a series of articulating links, means connected with one of said links with which said flexible connections are connected, a post connected with said slide and extending from another of said links into and through 60 the opening in said box, a pivot-post connected with and located at the side of said box, and a lever pivoted upon said pivot-post, said lever having a cam-slot into and through which the post of said slide extends. 65

nected, a post connected with said slide and extending from said slide into and through the opening in said box, a pivot-post connected with and located at the side of said box, and a lever pivoted upon said pivot- 70 post, said lever having a cam-slot into and through which the post of said slide extends.

2. An artificial limb comprising a main tubular wrist portion and a forwardly extending member connected with said wrist portion, a series of coiled springs, each spring being attached at one end-portion to said forwardly extending member, button-members mounted upon the free ends of said 75 springs, a cuff-attachment connected with and extending rearwardly from said tubular wrist portion, means connected with said cuff-attachment for securing said artificial limb to the mutilated portion of the limb of a person, flexible connections extending into and through said springs, said flexible connections being secured at one end to said button-members, a plate also connected with and extending rearwardly from said tubular 80 wrist portion, a box mounted upon said plate, said box being provided with an elongated opening, and an angularly disposed open portion in communication therewith, a slide within said box, said slide comprising a series of articulating links, means connected with one of said links with which said flexible connections are connected, a post connected with said slide and extending from another of said links into and through 85 the opening in said box, a pivot-post connected with and located at the side of said box, and a lever pivoted upon said pivot-post, said lever having a cam-slot into and through which the post of said slide extends. 90

3. An artificial limb comprising a tubular wrist-portion, a thumb-member and a plurality of finger-members extending forwardly from said wrist-portion, a chambered element extending rearwardly from said wrist-portion, a slide movably disposed within said chambered element, a post extending from said slide, a cam-lever pivoted to said chambered element, said lever being in engagement with said post for actuating said slide, and means in the form of tendons extending from said slide and connected with said thumb and finger-members for bringing the same into flexed positions. 100

4. An artificial limb comprising a tubular wrist-portion, a thumb-member and a plurality of finger-members extending forwardly from said wrist-portion, a chambered element extending rearwardly from said wrist-portion, a slide movably disposed within said chambered element, a post extending from said slide, a cam-lever pivoted to said chambered element, said lever being in engagement with said post for actuating said slide, means in the form of tendons 110

extending from said slide and connected with said thumb and finger-members for bringing the same into flexed positions, and and a stop-means connected with said chambered element with which said post is adapted to be brought into arrested engagement for retaining said slide in its rearwardly moved position.

5. An artificial limb comprising a tubular 10 wrist-portion, a thumb-member and a plurality of finger-members extending forwardly from said wrist-portion, a chambered element extending rearwardly from said wrist-portion, a plurality of articulating links 15 movably disposed within said chambered element, means connected with one of said links for actuating the same, and means in the form of tendons extending from another of said links and connected with said thumb 20 and finger-members for bringing the same into flexed positions.

6. An artificial limb comprising a tubular 25 wrist-portion, a thumb-member and a plurality of finger-members extending forwardly from said wrist-portion, a chambered element extending rearwardly from said wrist-portion, a plurality of articulating links 30 movably disposed within said chambered element, a post extending from one of said links, a cam-lever pivoted to said chambered element, said lever being in engagement with said post for actuating said links, and means in the form of tendons extending from another of said links and connected with said thumb and finger-members 35 for bringing the same into flexed positions.

7. An artificial limb comprising a tubular 40 wrist-portion, a thumb-member and a plurality of finger-members extending forwardly from said wrist-portion, a chambered element extending rearwardly from said wrist-portion, a plurality of articulating links 45 movably disposed within said chambered element, a post extending from one of said links, a cam-lever pivoted to said chambered element, said lever being in engagement with said post for actuating said links, means in the form of tendons extending from another of said links and con-

nected with said thumb and finger-members 50 for bringing the same into flexed positions, and a stop-means connected with said chambered element with which said post is adapted to be brought into arrested engagement 55 for retaining said articulating links in their rearwardly moved positions.

8. An artificial limb comprising a tubular 60 wrist-portion formed with a forwardly extending portion provided with marginal flanges, a plate secured to said wrist-portion between the said marginal flanges, said plate being provided with raised and laterally perforated retaining members, flexing finger-members, each member comprising a coiled spring, said springs having portions 65 of their coils threaded in the perforations of said retaining members for fixing said springs in position, and means connected with said springs and the wrist-portion for flexing said springs and the said finger-members.

9. An artificial limb comprising a tubular 75 wrist-portion formed with a forwardly extending portion provided with marginal flanges, a plate secured to said wrist-portion between the said marginal flanges, said plate being provided with raised and laterally perforated retaining members, flexing finger-members, each member comprising a coiled spring, said springs having portions 80 of their coils threaded in the perforations of said retaining members for fixing said springs in position, a plate-like member extending rearwardly from said wrist-portion, a box secured upon said rearwardly 85 extending member, a slide movably disposed within said box, means connected with said slide for actuating the same, and means also connected with said slide and with said springs for flexing said springs and the 90 finger-members.

In testimony, that I claim the invention set forth above I have hereunto set my hand this 17th day of May, 1918.

CHARLES HOFER.
